UNITED STATES PATENT OFFICE.

OTTO ARENDT, OF NEWARK, NEW JERSEY.

BOX-STRAP.

SPECIFICATION forming part of Letters Patent No. 773,271, dated October 25, 1904.

Application filed July 10, 1903. Serial No. 164,939. (No model.)

To all whom it may concern:

Be it known that I, OTTO ARENDT, a citizen of the United States, and a resident of Newark, county of Essex, State of New Jersey, have invented 5 certain new and useful Improvements in Box-Straps, of which the following is a specification.

My invention relates to that class of box-straps which is made of wire; and the object 10 of my invention is to provide a strap of that class which will lie flat against the box without being flattened and which will afford a suitable countersink for the head of the fastening-nails without cutting the wire.

To this end my invention consists in a twin 15 wire, the two strands of which are drawn so closely together as to be united at their inner edges, the strap thus formed being spread at suitable intervals by separating the two wires 20 sufficiently to admit the passage of a fastening-nail.

One application of my invention is shown in the accompanying drawings, in which—

Figure 1 is a top view. Fig. 2 is a section 25 on line 2 2 of Fig. 1. Fig. 3 is a section on line 3 3 of Fig. 1.

Same letters indicate similar parts in the different figures.

A B are two round wires of any convenient 30 size drawn through a die so close together as to be united at their inner edges, as shown in a, without leaving sufficient space for the entry of a nail-point. At convenient intervals these wires are forced apart to make an opening 35 C of suitable shape and size to allow the passage through it of the body of a fastening-

nail, but not of the head, the head resting upon the natural countersink formed by the rounded edges b b of the two wires. It will be seen that this strap provides a reversible 40 countersink, the rounded edges c c being similar to the other rounded edges. The strap therefore may be used either side up.

Among the advantages of my improved box-strap may be mentioned, first, that it combines 45 the lightness, strength, and cheapness of a round drawn wire with the capacity of lying flat against the box or package to which it is applied, and thereby not so likely to cut the floor or anything with which it may come in 50 contact, as would be the case if the wires were twisted over each other, so as to project more at some points than at others; second, a natural and reversible countersink is provided without weakening the strap by flattening or 55 cutting away any portion of the material. The thin head of the wire nail usually employed with these box-straps rests in this countersink with its outer edge flush with the surface of the strap, so that it cannot injure anything 60 with which it would otherwise come in contact and is not liable to become loosened in transportation.

I claim—

A box-strap formed of two round wires 65 closely united in parallelism along their inner edges and separated at intervals to provide nail-holes with reversible countersinks.

OTTO ARENDT.
